UNITED STATES PATENT OFFICE.

CHARLES E. WHITE, OF YOUNGSTOWN, OHIO.

FURNACE CLEANER.

Application filed February 14, 1927. Serial No. 168,187.

This invention relates to a furnace-cleaning apparatus, and one object of the invention is to provide an apparatus of this character, the elements of which may be mounted upon a truck and thereby easily transported from one place to another.

Another object of the invention is to so arrange the elements of the cleaning apparatus upon a platform forming part of the truck that they will be entirely disposed within the confines of the platform and thereby eliminate danger of their being damaged by striking obstructions while the truck is being moved from one place to another.

Another object of the invention is to cause the weight to be well distributed over the platform and thereby provide a balanced load.

Another object of the invention is to prevent the elements of the cleaning apparatus from being damaged by vibration when the apparatus is in use.

The improved furnace-cleaning apparatus is illustrated in the accompanying drawings, wherein

Figure 1 is a view showing the apparatus in side elevation;

Fig. 2 is a top plan view of the same;

Fig. 3 is a sectional view through the dust collector;

Fig. 4 is an enlarged fragmentary view through the lower portion of the dust collector and upper portion of the dust receptacle attached thereto, and

Fig. 5 is an enlarged fragmentary view illustrating the manner of releasably connecting sections of the hose forming a portion of the apparatus.

The furnace-cleaning apparatus constituting the subject-matter of this invention includes a truck which is of a conventional construction and indicated in general by the numeral 1. This truck is provided with a platform 2 which extends rearwardly from the driver's cab 3 and is formed with a flat uninterrupted upper surface. The platform is rectangular in shape and preferably of greater length than width. While the vehicle constituting the portable carrier has been illustrated as an automobile truck, it will be understood that any vehicle including a platform corresponding to the platform 2 may be employed.

The elements of the cleaning apparatus consist of a suction fan, indicated in general by the numeral 4, a fan operating motor 5

which operates the fan through the medium of a belt 6, a dust collector 7, a removable dust receptacle or bag 8 and a hose 9 leading from the inlet of the suction fan 4. By referring to Fig. 1, it will be seen that the motor 5 is mounted upon the platform 2 adjacent its forward end and at one side thereof and the fan 4 is firmly secured upon the platform rearwardly of the motor 5 and preferably above the rear axle of the truck. The dust collector 7 is disposed adjacent the front of the platform at the opposite side thereof from the motor 5 and consists of a casing 10 which is circular in top plan and is partially closed at its upper end by an annular flange or head 11. The lower portion 12 of the casing tapers downwardly and terminates in a reduced outlet spout 13 adapted to be passed through an opening formed in the platform 2 and project below the platform a sufficient distance to have the closure cap 14 applied thereto when the apparatus is not in use or the neck of the dust receptacle or sack 8 connected therewith. The sack 8 is formed of fabric and has its neck firmly secured about a metal ring 15 of such internal diameter that it may fit snugly upon the projecting lower end portion of the neck 13. Internal bayonet slots 16 are formed in the ring 15 and spaced from each other circumferentially of the ring for reception of the pins 17 which project radially from the neck. It will thus be seen that the receptacle may be firmly engaged with the neck of the collector but may be easily removed when the truck is to be moved or the receptacle becomes filled and needs to be emptied. In its upper portion the collector carries an annular air deflector 18 which extends downwardly from the head 11 and is intended to impart a whirling motion to dust laden air which enters the casing through the inlet pipe 19. This dust laden air moves downwardly through the casing in a spiral path and conveys the dust through the neck 13 into the sack 8 from which the air passes without carrying the dust with it. The pipe 19 extends diagonally across the platform and terminates in a downwardly curved free end portion 20 disposed above the outlet neck 21 of the fan 4 and connected with the outlet neck of the fan by a short section of flexible tubing 22, the ends of which are securely but removably fastened to the adjacent ends of the pipe and outlet neck.

By having the tube 22 formed of flexible material, such as reinforced fabric or the like,

the collector will not be affected by vibration of the rotary suction fan. This fan is of a conventional construction and includes the usual shaft 23 carrying a pulley wheel 24 about which passes the belt 6 which is engaged with the pulley wheel 25 carried by the shaft 26 of the motor 5. The pipe 9 or hose as it may be called has one end attached to the inlet of the suction fan. This hose is of sufficient length to reach from the truck to the furnace to be cleaned and is preferably formed of a number of sections 27 which may be of any desired length but are preferably six feet long and twelve inches in diameter. These sections are placed in end to end engagement with each other and have their adjacent ends releasably connected so that they may be taken apart or additional sections added if necessary. As a preferred means for connecting adjoining sections, I employ a split sleeve 28 of sufficient length to overlap the adjacent ends of the sections and of sufficient diameter to fit snugly about them. Straps 29 are passed about the end portions of the coupling sleeve and when tightened will cause the sleeve to be held in tight binding engagement with the hose sections. The hose may be coiled and placed upon the platform, as shown in Fig. 1, when not in use and additional pipe sections may be piled upon the platform rearwardly of the collector if so desired. By having the elements forming the cleaning apparatus mounted upon the platform, as shown in Figs. 1 and 2, the load will be very well balanced and no parts will project from the sides or ends of the platform. Therefore, they will not be liable to be struck when the truck is in motion and

damaged. When the device is in operation, the hose is extended from the truck into the cellar in which is located the furnace to be cleaned and the inner end of the hose applied to various portions of the furnace or pipes from which it is desired to remove soot. The suction of the fan draws the soot through the hose into the fan housing and expels it through the pipe 19 into the dust collector through which it passes into the bag 8. When the bag is filled, it can be easily removed and a new one substituted while the filled one is being emptied. After the furnace has been cleaned, the hose is again coiled upon the platform and surplus sections placed longitudinally upon the platform to the rear of the collector and the dust bag is removed and may be placed in the cab of the truck or upon the platform. The truck can then be driven to a new location without danger or injury to any of the apparatus carried thereby.

Having thus described the invention, I claim:

A cleaner of the character described comprising a dust collector including a downwardly tapered body terminating in a reduced outlet neck, an inlet pipe leading into the side of the body near the top thereof, a suction device, a flexible tube connecting the inlet pipe with the outlet of the suction device, radial pins on the reduced neck of the tapered body, a receptacle, and a ring in the top of said receptacle fitting closely around the neck and constructed to engage and be held by the pins thereon.

In testimony whereof I affix my signature.
CHARLES E. WHITE [L. S.]
